UNITED STATES PATENT OFFICE.

JOHN C. MILLER, OF WATERBURY, CONNECTICUT, ASSIGNOR TO THE MATTHEWS & WILLARD MANUFACTURING COMPANY, OF SAME PLACE.

WICK-ADJUSTER FOR CENTRAL-DRAFT LAMPS.

SPECIFICATION forming part of Letters Patent No. 576,876, dated February 9, 1897.

Application filed February 5, 1894. Serial No. 499,085. (No model.)

To all whom it may concern:

Be it known that I, JOHN C. MILLER, of Waterbury, in the county of New Haven and State of Connecticut, have invented a new Improvement in Wick-Adjusters for Central-Draft Lamps; and I do hereby declare the following, when taken in connection with accompanying drawings and the letters of reference marked thereon, to be a full, clear, and exact description of the same, and which said drawings constitute part of this specification, and represent, in—

Figure 1, a broken view, partly in section and partly in elevation, of a central-draft lamp provided with a wick-adjuster constructed in accordance with my invention; Fig. 2, a view thereof in transverse section on the line $\alpha\alpha$ of Fig. 1; Fig. 3, an enlarged sectional view showing the mode of connecting the spring-arms with the sleeve which surrounds the draft-tube.

My invention relates to an improvement in wick-adjusters for central-draft lamps, the object being to produce a simple, convenient, and effective device composed of few parts, not liable to derangement, and not requiring the exercise of skill in its manipulation or in wicking or unwicking the lamp.

With these ends in view my invention consists in a wick-adjuster having certain details of construction and combinations of parts, as will be hereinafter described, and pointed out in the claim.

In the accompanying drawings I have shown my improvement applied to a central-draft lamp having a fount A, a central draft-tube B, and a removable outer wick-tube C, all of well-known construction and not needing special description. The wick-holder consists of a sheet-metal tube or sleeve D, constructed to fit over the draft-tube B and to slide freely up and down thereupon. It is formed near its upper edge with an outwardly-projecting rib D', which is struck out from its inner face. As herein shown, the face of this rib is broad and flat and located in a plane parallel with the plane of the band, but such form is not essential and may be varied, if desired. Pairs of vertically-arranged perforations d d, formed

in the base of the said rib, are provided to receive fingers E, formed integral with the lower ends of independently-formed wick-gripping arms E', the extreme upper ends of which are toothed and bent outwardly for engagement with the wick, the said arms being formed of steel or equivalent material. As herein shown, I have employed three of these arms, but I may employ two or more, as may be desired. They are arranged in vertical positions and are therefore parallel with each other, and in the operation of the lamp bear throughout the greater portion of their length directly upon the wick-tube, between which and them sufficient friction is developed to hold the band, and hence the wick, in any desired position of elevation. The said arms are constructed near their lower ends with shoulders e e, which rest upon the upper edge of the rib D' of the tube or sleeve D and thus prevent their downward displacement. The arms are also secured to the sleeve by means of rivets F, one of which is passed through the projecting lower end of the finger of each arm, as clearly shown in Figs. 1 and 3. By making the rib with a broad flat face it affords a long bearing for the fingers of the spring wick-gripping arms, and hence the advantage of making the rib in that form. The base of the rib is also constructed with vertically-aligned openings d' d' for the reception of the upper end of a flat spring sheet-metal strap G, employed to connect the wick-holder with the straight rigid draw-bar H, the projecting upper end of the said strap being secured to the sleeve at a point above the rib D' by a rivet g. For the purpose of connecting the lower ends of the strap and bar the latter is bent to form an inwardly-projecting horizontally-arranged hook H', which extends crosswise, so to speak, of the draft-tube, and which, as shown, receives the extreme end g' of the strap G, the said end of the strap being bent upon itself into the form of an open tube g' to fit around the said end of the hook. Said bar is located in an inclined position and plays up and down at its upper end in an inclined bearing I, secured to the top of the fount A. The strap G is also bent to form a stop-

shoulder G', which, when the bar and wick-holder are elevated, engages with the collar C', formed at the lower end of the outer wick-tube C, and limits the upward movement of 5 the wick-holder, which it stops in its upward movement at a point below where the spring-arms E' are allowed to spring inward over the top of the draft-tube for disengaging the wick. The spring-strap therefore acts as a 10 fender for preventing the wick-gripping arms from being raised above the top of the draft-tube. The said spring also acts as a tension device, for it either pushes or pulls upon the draw-bar, according to the vertical position 15 thereof, so as to cause the same to bind in its bearing in the lamp-fount, the binding of the draw-bar in the manner described assisting to hold the wick in any desired position of adjustment. The spring has still a further 20 function in assisting in gaging the position of the wick when the same is applied to the sheet-metal tube or sleeve D.

It will be understood that as the draw-bar is raised and lowered its end will, on account 25 of its inclination with reference to the central draft-tube, move away from and toward the same, this movement being compensated for by the springing of the connecting-strap G. By removing the outer wick-tube C the 30 bar may be raised so as to project the upper ends of the spring-arms E' above the central draft-tube, whereupon they will spring inward toward each other and release the wick. They are therefore brought into the position 35 described for releasing the wick preparatory to its removal and for placing the wick in position to be permanently engaged by them in the process of wicking the lamp.

It will be seen that my improved device is 40 very simple in construction and not liable to derangement, and that its operation both in raising and lowering the wick and for removing and renewing the same is so simple as to be readily effected by a child or servant.

45 I would have it understood that I do not limit myself to the exact construction herein shown and described, but hold myself at liberty to make such changes and alterations

as fairly fall within the spirit and scope of my invention.

I am aware that a sheet-metal band or sleeve adapted to ride directly upon the draft-tube of a central-draft lamp and provided with integral wick-gripping jaws extending above its upper edge and also arranged to ride upon the draft-tube, is old. I am further aware that it is old to make such jaws independent of the sleeve or band and connect their lower ends therewith. I am further aware that it is old to employ a spring connection between the lower end of a draw-bar and a wick-holder riding up and down on a central draft-tube. I do not, therefore, claim any of these constructions broadly.

Having fully described my invention, what 65 I claim as new, and desire to secure by Letters Patent, is—

In a wick-adjuster for central-draft lamps, the combination with a lamp-fount, of a central draft-tube located therein, a wick-holder 70 movable up and down upon the said tube, a straight, rigid draw-bar mounted in an inclined position in the lamp-fount, having its upper end extended upward through the same, and its lower end bent to form an 75 inwardly-projecting, horizontally-arranged hook extending crosswise of the draft-tube, a spring connecting-strap having its upper end attached to the wick-holder and its lower end bent for engagement with the said hook 80 of the bar, and an inclined bearing located upon the lamp-fount, and adapted to receive the draw-bar which it confines to movement in an inclined plane, the variation in the distance of the lower end of the bar from the 85 draft-tube and wick-holder caused by pulling it up and pushing it down, being permitted by the said spring connecting-strap, substantially as described.

In testimony whereof I have signed this 90 specification in the presence of two subscribing witnesses.

JOHN C. MILLER.
